[57] CLAIM

The ornamental design for a screwable container, as shown and described.

DESCRIPTION

FIG. 1 is a side view of the screwable container showing my new design;

FIG. 2 is an exploded perspective view thereof; and,
FIG. 3 is another side view of the screwable container showing my new design.

With the exception of a ring attached to a cover of the container by means of a hole passing through the cover, the container and its cover are symmetrical about a longitudinal axis of the container. The lettering shown in FIG. 1 does not form a part of the design.
